INVENTOR

BY *Victor J. Evans*

J. M. Evans

WITNESS:

UNITED STATES PATENT OFFICE.

JESSE C. JOHNSON, OF DELRAY, FLORIDA.

AEROPLANE.

Application filed September 4, 1923. Serial No. 660,875.

To all whom it may concern:

Be it known that I, JESSE C. JOHNSON, a citizen of the United States, residing at Delray, in the county of Palm Beach and State of Florida, have invented new and useful Improvements in Aeroplanes, of which the following is a specification.

The present invention relates to aircraft, and consists in the combination and arrangement of elements hereinafter described and particularly set forth in the appended claim.

The purpose of the invention is to provide an aeroplane with revoluble lifting, traction, alighting and control helicopters which may be employed in connection with or independently of the ordinary traction propeller and planes, and wherein speed and safety in flight is positively assured.

Another desirable feature is the provision of revoluble traction helicopters arranged in pairs at the opposite sides of the craft, operated in unison but in reverse directions by a suitable motor and capable of swinging movement from horizontal to substantially vertical positions in either direction with respect to the craft, and whereby the craft may be raised, propelled in a straight ahead direction, caused to assume desired angles and to alight in an easy and safe manner, means, of course, being employed for sustaining the revolving helicopters in any of their various positions.

It is also my purpose to provide propelling means for an aeroplane which not only materially increases the speed thereof but affords a positive control for the craft as well as a safety device therefor inasmuch as the construction is movable to meet all wind conditions and is so arranged on the craft as to prevent the side tilting thereof.

In addition to the foregoing, the invention possesses other features of value which will be clearly apparent from the following description when taken in connection with the drawings.

In the drawings:—

Figure 1 is a side elevation of an aeroplane provided with the improvement.

Figure 2 is a top plan view thereof.

Figure 3 is a sectional view on the line 3—3 of Figure 1, looking toward the arrows.

Figure 4 is a similar sectional view on the line 4—4 of Figure 1.

Figure 5 is a fragmentary sectional view approximately on the line 5—5 of Figure 2.

Figure 6 is a diagram, illustrating in plan the connection between the motor shaft and the shafts of the revoluble planes, the latter being in section.

The invention as shown in the drawings is incorporated in a flying machine of the bi-plane type, but is, of course, susceptible to successful employment in other type of aircraft.

Referring now to the drawings in detail, the fuselage 1 of the craft is of the ordinary cigar-shape construction, the cock pit thereof being indicated by the numeral 2. The fuselage or body 1 may have at its nose end the usual traction propeller 3 and has at its tail end the usual elevating and guide rudders, operated by guy wires leading to the lower portion of the body and into the cock pit.

The craft may also be provided with laterally extending upper and lower planes 4 and 5 which preferably have ailerons associated therewith and operated from the cock pit in the usual manner. The planes are arranged in a line with the center of gravity.

In the body of the craft there is a motor 6 of the usual type employed upon this class of devices, the propelling shaft therefor being indicated by the numeral 7, and the said shaft may be connected directly to the traction propeller 3, when the latter is employed, or may be operated by the usual motor when my improvement is employed as an attachment to an ordinary aircraft.

The motor shaft 7 has secured thereon spaced worms 8 and 9 respectively. The number of worms on the shaft is optional, as only the outer worm 9 may be employed, while, in addition to the worm 8 other worms may be utilized. Also in lieu of worms other class of gears may be employed. Each worm or gear is in mesh with a gear or worm wheel 10 centrally secured on transversely arranged shafts 11. Each shaft has keyed on its outer end a beveled gear 12. The worm or gear portions of the motor shaft 7 are arranged in suitable housings 13, and the said shaft 7 may be encased in a protective housing which may be bolted to the housings 13. Each housing 13 has lateral centrally disposed tubular extensions 14 whose ends are flanged and bolted to the sides of the body, and these extensions are in alignment with similar tubular members 15 which have their inner ends flanged and

likewise bolted to the body of the craft. In the lateral tubular extensions of the housings there are sleeves 16, and it is in these sleeves that the shafts 11 find direct bearings. The sleeves also serve to prevent lubricant in the housings seeping through the tubular ends thereof.

Each sleeve 16 has formed on its outer end a substantially inverted L-shaped casing 17. The casings have removable face plates, and the said casings receive therein the beveled gears 12. In the second branch of each casing 12 there is received a beveled gear 18 in mesh with the respective wears 12. The gears 18 are secured on the ends of shafts 19 which are mounted for rotation in tubular bearing sleeves 20 that are secured to the outer angle branches of the casing 17. The tubes 20 are sustained in parallelism 20 by transverse braces 21.

On each of the shafts 19, at the end thereof projecting through its bearing 20 there is secured a rotary helicopter 22. In the showing of the drawings the helicopters are 25 in the nature of two blade propellers, but, it is to be understood that the helicopters may embody any desired number of blades and may be constructed in various manners, so I am not to be restricted to any particular shape or construction in this respect.

Preferably the transverse braces 21 are in the nature of pipes and have their ends screwed in couplings 23 on the tubular bearings 20, whereby the said braces may be adjusted. Also preferably the tubular braces are formed of sections which have their confronting ends screwed into the said couplings 23.

The couplings 23, right angularly with respect to the branches thereof in which the brace members 21 are received, have their confronting faces formed with ears 24 that receive the bifurcated ends of longitudinal brace rods 25. Pivots 26 secure the ears 24 45 in the ends of the brace rods.

The outer fixed transverse brace 21 has centrally swung thereon a depending, preferably angularly disposed link 30. The link is pivoted, as at 31 between upstanding ears 32 formed in a line with the longitudinal walls provided by the elongated slot 33 in the top of the body 1, forward of the cock pit 2. The link has the end which extends into the body of the craft widened and 55 formed with an elongated opening 34. This opening receives therethrough a pin 35 formed with or secured to a lug or ear 36 on a traveler 37. The traveler is in the nature of a sleeve having its bore threaded, and engaging the threads of the said bore there are threads formed on a rod 38. The rod has its outer end journaled in a bearing bracket 39 suitably secured in the body 1, and has its opposite end passing through a bearing sleeve 40 into the cock pit 2. This end of

the rod is provided with a crank handle 42.

The craft 1 is provided with alighting wheels 43. The motor 6 is under the control of the aviator or his mechanic, and the helicopters 22 are in the position illustrated 70 in Figure 1 and in Figure 3 when the craft has landed or is about to ascend. In the latter event the motor is put in motion to operate the shafts 19 which revolve the helicopters 22. It is to be understood that the 75 helicopters on the opposite sides of the craft revolve in a reverse direction and toward each other. The revolving of the helicopters will lift the craft so that the same arises in a straight vertical direction. When the craft is to be driven in a straight ahead direction the crank handle 42 is operated to turn the rod or shaft 38 to swing the link 30 to bring the helicopters to a forward vertical position. Because of the arrangement of the 80 helicopters on the opposite sides of the craft danger of side tilting of the aeroplane will be positively prevented, and also because of this arrangement a far greater speed may be maintained by the craft than by an ordinary construction of aeroplanes. When the craft is to alight the shaft or rod 38 is turned in an opposite direction so that the helicopters 22 will be swung to the rear of the craft and to a substantially vertical position. The 85 helicopters thus reversely act upon the wind currents so that the craft will descend and safely alight at any desired point. By arranging the helicopters at varying angles varying conditions of the wind may be successfully met so that the craft may be propelled and steered regardless of weather conditions.

It is thought that the simplicity and advantages of my construction will, from the foregoing description in connection with the drawings, be perfectly apparent to those skilled in the art to which such improvements relate, but I desire it understood that I am not to be limited to the precise construction, arrangement of parts, material employed and such like details, and therefore hold myself entitled to such changes and modifications therefrom as fall within the scope of what I claim.

Having described the invention, I claim:

In an aeroplane, a motor driven shaft, transverse shafts extending through the sides of the aeroplane driven by said first mentioned shaft, housings for the shafts, bearing sleeves for the last mentioned shafts in the lateral branches of the housings, inverted L-shaped casings on the ends of the sleeves, gears therein secured to the lateral shafts, upright bearing sleeves secured on the casings, shafts journaled therein having gears meshing with the first mentioned gears, a helicopter on each of the last mentioned shafts, adjustable transverse brace

means for the last mentioned sleeves, pivotally secured longitudinal brace means for said sleeves, an arm depending from the outer transverse brace means, a pivotally supported slotted link therefor, an interiorly threaded traveler having a pivot passing through the slot of the link, a threaded rod journaled in bearings received through the traveler and having a cranked end received in the cock pit of the craft, all as and for the 10 purpose set forth.

In testimony whereof I affix my signature.

JESSE C. JOHNSON.
